Primary Examiner — Sandra Snapp(74) *Attorney, Agent, or Firm* — Law Offices of Robert F. Zielinski, LLC(57) **CLAIM**

The ornamental design for a seating unit with base, as shown and described.

DESCRIPTION

FIG. 1 is top, side, right perspective view of the seating unit with base embodying our new design.

FIG. 2 is a front view of the seating unit with base thereof.

FIG. 3 is a rear view of the seating unit with base thereof.

FIG. 4 is a right side view of the seating unit with base thereof.

FIG. 5 is a left side view of the seating unit with base thereof.

FIG. 6 is a top plan view of the bottom side of the seating unit with base thereof.

FIG. 7 is a bottom view of the bottom side of the seating unit with base thereof; and,

FIG. 8 is an exploded top, side right perspective assembly view of the seating unit with base thereof.

The broken line representations in the figures show unclaimed environment, and thus form no part of the claimed design.

The nature of this product is a seating unit with base for supporting a human in a seated position.
